MINIATURE INCANDESCENT LAMP

**John F. Donovan, East Cleveland, Ohio, assignor
to General Electric Company, a corporation of
New York**

Application June 20, 1935, Serial No. 27,503

4 Claims. (Cl. 176—32)

My invention relates to electric lamps and more particularly to the base or terminal portion thereof, when fitted into an appropriate socket, completes the electrical connection of the lamp to a source of electrical energy. One object of my invention is to provide a simple, durable and inexpensive base which will allow the lamp to be very conveniently inserted in a socket and removed therefrom. My invention is particularly adaptable to miniature lamps of the type used for decorative purposes. Further features and advantages of my invention will appear from the following description of species thereof and from the drawing.

15 In the drawing Figs. 1 and 2 are front and side elevations of an incandescent lamp comprising my invention; Fig. 3 is a section at the line 3—3 of Fig. 2; Fig. 4 is a modification; Fig. 5 is a section at the line 5—5 of Fig. 4; Fig. 6 is a somewhat diagrammatic elevation partly in section of apparatus used in the manufacture of the modification in Fig. 4; and Fig. 7 is an elevation, partly in section, of a receptacle having one of the lamps comprising my invention mounted therein.

Referring to Figs. 1 to 3, the lamp comprises a bulb 10 having a reduced cylindrical neck portion 11 and containing a filament 12 mounted on lead wires 13 which are held in spaced relation by a glass bead 14. The lamp is of the butt-seal type in which portions of the leads 13 are sealed in the glass of the joint formed by the end of the neck 11 of the bulb and the exhaust tube 15 which is sealed off as shown after the bulb has been evacuated. The outer leads 16 extend longitudinally on opposite sides of the neck 11 to serve as terminals. The said outer leads 16 are held in place by a gummed band of insulating material 17, such as paper, which encircles the neck 11 adjacent the bulb 10 over the ends of said outer leads. In order to insure that the lamp is correctly inserted in a socket and to prevent it from rotating therein, the neck portion 11 is preferably provided with a pair of longitudinally extending protuberances 18 which are preferably blown therein at the time the bulb is blown.

50 In the modification shown in Figs. 4 and 5, the outer leads 16 are held in place by a band 18 of plastic insulating material, such as sealing wax or cement, encircling the neck 11 of the

5
bulp and having protuberances 20 in which the
said outer leads are embedded. The said band
19 may be applied to the neck portion 11 of the
bulp from the periphery of a rotating disc or
wheel 24 (Fig. 6) which carries the insulating ma-
terial up from a container 25 and is brought in
contact with the said neck 11 to deposit the in-
sulating material thereon. The periphery of the
said wheel is provided with notches 26 which car-
ry an excess of the insulating material to form 10
the protuberant portions 20 of the band 19.

In Fig. 7, the lamp 10 is shown mounted in a receptacle 21 of the imitation candle type which comprises a tube 22 of insulating material, such as cardboard having a pair of arcuate terminal members 23 mounted therein. The longitudinal protuberances 18 on the bulb neck 11 fit between the sides of the terminal members 23, it being impossible to insert the lamp in any other position. The said protuberances 18 thereby insure that the lamp is correctly positioned in the receptacle or socket so that the outer leads 16 are in contact with the socket terminals 23, and they also prevent rotation of the lamp in the socket so that the leads 16 cannot be twisted off. 25

What I claim as new and desire to secure by Letters Patent of the United States is:

1. An electric lamp comprising a bulb having a neck portion, a pair of lead wires having portions thereof sealed in the walls of said neck portion and extending longitudinally of said neck portion on opposite sides of the outer surface thereof and a band of insulating material encircling said neck portion of said bulb and the ends of said lead wires for holding said lead wires in position on said neck portion of said bulb.

2. An electric lamp comprising a bulb having a neck portion, a pair of lead wires having portions thereof sealed in the walls of said neck portion and extending longitudinally of said neck portion 40 on opposite sides of the outer surface thereof and a band of plastic insulating material encircling said neck portion of said bulb and having the ends of said lead wires embedded therein for holding said lead wires in position on said neck portion of 45 said bulb.

3. An electric lamp comprising a bulb having a neck portion, a pair of lead wires having portions thereof sealed in the walls of said neck portion and extending longitudinally of said neck portion 50

on opposite sides of the outer surface thereof, a band of insulating material encircling said neck portion of said bulb and the ends of said lead wires for holding said lead wires in position on said neck portion of said bulb, and an integral longitudinally extending protuberance on said neck portion of said bulb.

4. An electric lamp comprising a bulb having a neck portion, a pair of lead wires having portions thereof sealed in the walls of said neck portion

and extending longitudinally of said neck portion on opposite sides of the outer surface thereof, a band of plastic insulating material encircling said neck portion of said bulb and having the ends of said lead wires embedded therein for holding said lead wires in position on said neck portion of said bulb, and an integral longitudinally extending protuberance on said neck portion of said bulb.

JOHN F. DONOVAN. 10
